UNITED STATES PATENT OFFICE.

ALBERT W. MITCHELL, OF NEW HAVEN, CONNECTICUT, ASSIGNOR TO JOHN N. LEONARD, TRUSTEE, OF NEW HAVEN, CONNECTICUT.

PAPER-BOX MACHINE.

No. 862,835.

Specification of Letters Patent.

Patented Aug. 6, 1907.

Application filed March 14, 1907. Serial No. 362,320.

To all whom it may concern:

Be it known that I, ALBERT W. MITCHELL, a citizen of the United States of America, residing in the city of New Haven, in the county of New Haven, in the State 5 of Connecticut, have invented certain new and useful Improvements in Paper-Box Machines, of which the following is a specification.

My invention relates to that class of machines in which paper boxes are formed from blanks which are 10 scored or cut, and the sides are bent or folded up and the glued or pasted ends are folded together over a plunger or former.

My invention is more particularly intended as an improvement in the construction of the forming and folding 15 mechanism of the paper box machines for which I applied for Letters Patent June 6th, 1906, Serial No. 320,486, and in which a stationary die is combined with an endless chain of plungers or formers passing through the die in succession.

20 In the accompanying drawings Figure 1 is a sectional elevation through the die showing the plunger as it passes into the blank and is about to force the latter through the die; Fig. 2 is a sectional plan on the line 2—2, Fig. 1; Fig. 3 is a view similar to Fig. 1, but showing the folding fingers retracted and the plunger passing into the die; Fig. 4 is a corresponding plan view; Fig. 5 is a sectional plan view drawn to a larger scale, and showing one of the folding fingers in its retracted position; Fig. 6 is a similar view, showing the fingers projected to the folding position; and Fig. 7 is a sectional 25 view showing means for yieldingly supporting the wings to shape the bottom of the box.

In these drawings, C is the bed plate of the machine, P is one of the plungers or formers, carried by a laterally 30 projecting arm p, on a link P¹, which is to be connected up to like adjacent links of the endless chain by pairs of short links p¹. A continuous travel may be imparted to the endless chain of plungers P so that the latter pass through the forming die D in succession. In the edge 35 of the die-opening is formed a notch d, (Fig. 2) for the passage of the arms p, which carry the plungers.

On opposite sides of the die D, above the table C, I provide side plates 55, which are in effect continuations of the guides on the table top which maintained bent 40 upright the sides of the paper blank to form the side walls of the box, as the paper web has been intermittently fed forward in the direction of the arrow, Fig. 2, towards the die D over the surface of the table C.

The devices so far described are substantially the same 45 as like parts found in the machine of my above described application.

One of the features of my present invention consists in the improved mechanism for folding the end flaps f, of the sides of the blank over the ends of the rectangu-

lar former or plunger P, before it carries the blank 55 through the die to thereby fold up the end flaps of the bottom over the inturned side flaps.

The folding devices comprise at each end of the box a pair of folding fingers 59 and 60, which are guided in slots in the side walls 55 and are projected inwardly by 60 suitable means at the proper time to fold the end flap f, of the sides of the blank up against the end walls of the former P, (Figs. 1 and 2), and then at the proper moment are withdrawn again, as shown in Fig. 3. For this purpose, each finger 59 is mounted by a vertical 65 pivot upon the upright portion 57 of a horizontal slide 58 free to reciprocate in guides 56 on the table C. Short reciprocating motion may be applied intermittently by any suitable means from a moving part of the machine. In Figs. 2 and 4, I have indicated for this purpose 70 an upright rock shaft 61 connected by a crank arm 62 to the slide 58. The upper part of the upright 57 on the slide 58 is connected by rods 65 to the upper ends of two levers 64, which are pivoted on horizontal pivots 63 on lugs on the right hand side wall 55, and at their lower 75 ends have pivoted to them the folding fingers 60. Thus when the slide 58 is moved inwardly to project the fingers 59 across the ends of the plunger or former P, the fingers 60 are simultaneously projected inwardly at the opposite side.

An important feature of the invention consists in the provision of means for imparting to the folding fingers a movement towards and from the ends of the former P, as well as across the ends. For this purpose, I form on the outer face of each finger a cam surface 66, (Figs. 2, 5 85 and 6), which can bear against the outer edge of the slot in the side wall 55, so that as each finger is projected through the wall from its retracted position shown in Fig. 5 to its folding position, Fig. 6, the cam 66 riding on the edge of the slot will cause the finger 59 (60) to move 90 up towards the end face of the former P and press the flap f of the blank against the latter accordingly. The manner of pivoting the fingers 59 readily permits of this, while in the case of the fingers 60, the like movement may be permitted by allowing a certain freedom of 95 movement of the levers 64 on their pivots 63.

By the time the fingers 59, 60, have folded the side flaps f, the plunger P will have started to press the box blank through the die D, and in doing so will fold up the gummed outer or bottom flaps over the side flaps f.

In order to get a more satisfactory action of the plunger P on the blank, when the plunger P descends into the partially folded blank, and to obtain sharper corners on the bottom of the finished box body or cover, (as the case may be), I provide along the side walls 55 just over 100 the die D yielding supporting wings 95 hinged at 96, and normally maintained in the horizontal position shown in Figs. 1 and 7 by any suitable means, such as a

spring 97, connecting arms 98 on the axles 96 of the wings. These wings when in their horizontal position are flush with the surface of the feed table so that the folded box blank is fed onto the wings as it passes between the side walls 55. Thus while the plunger P is descending into the blank, the latter will be supported by the wings 95, until the plunger presses the bottom of the box firmly against these wings and then pushes the latter back on their hinges, as shown in Fig. 3.

10 I claim as my invention

1. A paper box machine, having a plunger and die with fingers for folding the side flaps against the end walls of the plunger and means for reciprocating said fingers in a direction across said end walls, and means for simultaneously moving the fingers towards or from said end walls.

2. A paper box machine having a plunger and die with slotted side walls over the die, folding fingers to be projected through such slots and having cam faces and means for intermittently projecting and withdrawing the fingers. 20

3. A paper box machine, having a feed table for the box blanks, a plunger and die with side walls over the die and yielding supporting wings normally held over the die flush with the surface of the feed table to support the blank while the plunger descends into it, whereby the boxes are 25 formed with sharp corners.

In testimony whereof I have signed my name to this specification, in the presence of two subscribing witnesses.

ALBERT W. MITCHELL.
